(57) CLAIM

The ornamental design for a floor lamp, as shown and described.

DESCRIPTION

FIG. 1 is a perspective view of the floor lamp of my design; FIG. 2 is a front view of the floor lamp (the back view, being a mirror image of the front view, is not shown; the right side view and left side views are also identical to the front view, and are also not shown);

FIG. 3 is a top view of the floor lamp; and,

FIG. 4 is a bottom view of the floor lamp.
